UNITED STATES PATENT OFFICE

THEODORE E. ARKIN, OF CHICAGO, ILLINOIS

DANCING APPARATUS

Application filed July 1, 1929. Serial No. 375,102.

The present invention relates to dancing apparatus and more particularly to apparatus adapted to produce sparks by the engagement of the shoes of the dancer with the floor upon which the dancing is performed, one object of the invention being to provide apparatus of this character of a simple and inexpensive form which will produce an effective display of sparks with a minimum of equipment. Another object is to provide apparatus of this character by which copious quantities of sparks may be produced by the dancer merely by means of frictional engagement of the dancer's shoes with a suitable floor surface.

To these and other ends the invention resides in certain improvements and combinations of parts, all as will be hereinafter more fully described, the novel features being pointed out in the claims at the end of the specification.

In the drawings:

Fig. 1 is a view showing a preferred embodiment of the present invention; and
Fig. 2 is a detail view illustrating the sole of a shoe equipped with a metal plate in accordance with the preferred form of the invention.

Similar reference numerals throughout the several views indicate the same parts.

Attempts have heretofore been made with varying degrees of success to provide dancing equipment by which sparks might be produced by contact of the dancer's shoes with a suitable medium. This has involved the use of expensive and cumbersome equipment such as electric batteries and wires concealed in the clothing of the dancer and adapted to produce sparks due to the making and breaking of an electric circuit. The present embodiment of the invention provides an apparatus of a greatly simplified form, which is negligible in weight and of a construction which is simple and easy to manufacture without requiring any special tools or machinery.

The invention as disclosed includes the use of two materials one of which is preferably of an abrasive nature and the other of which preferably comprises a hardened metal. One of the materials is suitably incorporated in

or on the soles of the dancer's shoes so as to be available for ready frictional engagement with the other material which is incorporated in the surface upon which the dancing is performed.

Referring more particularly to the drawings, numeral 5 designates a shoe of more or less ordinary form suitable for what is ordinarily termed tap or clog dancing. A plate 6 of suitable material is secured to the shoe, preferably the toe portion, in any desired manner, as for example, by means of screws 7. While this plate may be formed from various materials, in the preferred embodiment of the invention, it is formed from a good grade of tempered tool steel. If desired one or more additional plates of the same or similar material may be secured at other points on the sole of the shoe as indicated, for example, at 8. Obviously any number of similar plates according to the particular desires of the dancer may be secured to the shoe and it is also obvious that these plates may take various shapes and forms.

In the case where metallic plates are used on the soles of the dancer's shoes a suitable abrasive material or substance is incorporated in the surface on which the dancing is to be done. While the abrasive substance could be incorporated in a permanent portion of the floor of a stage it is preferable for most purposes to have this abrasive material incorporated in a mat which can be removed from the floor at will and easily transported in a suitable container or stored in an out-of-the-way place. As shown in Fig. 1, there is provided a mat 9 formed from a suitable strong fabric such as linoleum or a similar firm texture and relatively stiff material. On the upper surface of the mat 9 there is provided a layer 10 of any suitable abrasive material such as emery or carborundum. The mat could also be made with a surface of ordinary finely crushed commercial flint or so called "sparking stone" such as is used in cigar lighters and similar lighters. It has been found after experimentation that ordinary commercial emery cloth gives very satisfactory results.

In place of plates of tempered steel se- 100

cured to the shoe very excellent results can be obtained by securing pieces of so called 5 sparking stone in the sole of the shoe and using the emery mat. The sparks from this combination are somewhat more brilliant than sparks obtained from steel on emery. In the case where sparking stones are used in the shoe soles the material of the mat could be varied and, instead of using an emery 10 surface, a hard abrasive metallic surface having the characteristics of an ordinary metal file could be used.

The use and operation of the apparatus just described will be apparent to any one familiar 15 with tap and clog dancing. The dancer, whose shoes are provided with plates such as described, will usually give an exhibition of his dancing skill on a brightly lighted stage and on a portion of the stage floor not covered 20 with an abrasive substance. The audience will not be able to observe anything unusual in the construction of the dancer's shoes and it will therefore appear that the dancer is giving a more or less usual form of exhibition of 25 dancing skill.

After the dancer has had an opportunity to display his skill on a brightly lighted stage the apparatus embodying the present invention may be used as a surprise element of the 30 performance by having the stage quickly darkened whereupon the dancer will move to a different portion of the stage where the mat 9 has been placed and will continue his performance thereon. As soon as the plates on 35 the dancer's shoes begin to frictionally engage with the abrasive surface 10 a brilliant display of sparks from the dancer's feet will be observed. The construction of the mat and the shoes is such that not only will the 40 usual sounds be made by the dancer's feet in time to the music but in addition there will be a display of sparks forming a definite appeal to the eyes of the audience. Obviously 45 the dancer may add to the effectiveness of the display by wearing clothing which has been treated with radium paint or similar substances to cause it to glow in the dark.

It will be apparent from the foregoing that 50 there is thus provided a very simple, inexpensive and reliable dancing apparatus which is available at all times for use without depending upon a more or less uncertain form of equipment such as electric batteries and pyrotechnic substances. It will be also apparent that the invention is not necessarily 55 limited to the particular arrangement of materials illustrated in the drawings but that it is possible to obtain satisfactory sparking 60 effects where the abrasive material is secured on the soles of the dancer's shoes and the metallic plate forms at least a portion of the floor. In some instances it may be desirable to put a mixture of each of the several 65 sparking substances on the shoes and the

same mixture on the floor surface in about equal proportions.

While the invention has been described as being applied to a dancer's shoes it is equally obvious that equally effective results can be 70 obtained by the use of the hands. For example, a glove could be made provided with metal plates or with emery for producing sparks when rubbed against a complementary 75 sparking surface. This surface need not in all cases be on the floor but obviously could be located elsewhere as for example a pair of gloves could be used in which one glove was provided with a sparking substance complementary to the other glove. Also the sparking 80 surface could be located at convenient points on the dancer's body to be struck by a glove having a complementary surface. It is to be understood therefore that where reference is made in the appended claims to 85 the dancer's feet or shoes and to the floor surface these terms are to be construed broadly enough to include other manipulatory parts on the dancer's body and to include any convenient surface adapted to be engaged 90 thereby.

While the present description sets forth a preferred embodiment of the invention, numerous changes may be made in the construction without departing from the spirit 95 of the invention, and it is therefore desired that the present embodiment be considered in all respects as illustrative and not restrictive, reference being had to the appended claims rather than to the foregoing description to 100 indicate the scope of the invention.

I claim:

1. Dancing apparatus comprising in combination two complementary materials adapted to produce sparks when frictionally 105 engaged one with the other, one of said materials being secured to the footwear of a dancer and the other of said materials forming at least a portion of the surface upon which dancing is to be performed. 110

2. Dancing apparatus comprising in combination an article of footwear and an abrasive surface upon which dancing is to be performed, said article of footwear including a material which when frictionally engaged 115 with said abrasive surface will cause the production of sparks.

3. Dancing apparatus comprising in combination a shoe in which a portion of the sole thereof is formed of a sheet of hardened, tempered steel and a floor surface on which the dancing is to be performed, said floor surface being provided with an abrasive substance adapted to produce sparks when the steel portion of the shoe is frictionally rubbed 125 thereagainst.

Signed at Chicago, Illinois, this 29th day of June, 1929.

THEODORE E. ARKIN.
